STORAGE RACK

Kurt E. Christoffersen, Gales Ferry, Conn., assignor to Artistic Wire Products Co. of Conn., Incorporated,
Norwich, Conn., a corporation of Connecticut

Filed Nov. 1, 1960, Ser. No. 62,691

Term of patent 14 years

(Cl. D44—29)

FIG. 1

FIG. 2

FIG. 3

FIG. 4

FIG. 5

Fig. 1 is a perspective view of a storage rack embodying my new design.

Fig. 2 is an elevational side view thereof.

Fig. 3 is a plan view of said storage rack.

Fig. 4 is an elevational end view thereof.

Fig. 5 is an end elevational view of a modified form of my new design, wherein the outer legs are straight and the cup supporting hooks depend from a horizontal extension of the legs.

I claim:

The ornamental design for a storage rack, substantially as shown and described.
